COMPARTMENTED TRAY FOR DRAFTING SUPPLIES

Richard W. Chatham, Rte. 10, P.O. Box 823, Sherre Lane,
Greensboro, N.C. 27406

Filed Sept. 9, 1974, Ser. No. 504,305

Term of patent 14 years

Int. Cl. D9—03

U.S. CL. D9—185

FIG. 2

FIG. 1 is a front perspective view of a compartmented tray for drafting supplies shown by my new design; and

FIG. 2 is another perspective view showing the side not seen in FIG. 1.

The bottom and rear are plain and unornamented.

I claim:

The ornamental design for a compartmented tray for drafting supplies, as shown and described.
